United States Patent Office.

JOHN T. WEBSTER, OF NEW YORK, N. Y.

Design No. 3,403, dated March 2, 1869.

DESIGN FOR A FLOOR OIL-CLOTH PATTERN.

The Schedule referred to in these Letters Patent and making part of the same.

To all whom it may concern:

Be it known that I, JOHN T. WEBSTER, of the city of New York, in the county of New York, and State of New York, have originated and designed a new Pattern for Floor Oil-Cloths, of which the following is a full, clear, and exact description, reference being had to the accompanying drawings, making part of this specification.

The drawings, painted in colors, on what is known as design-paper, represent a complete design for floor oil-cloths.

This design, when repeated or reversed on the ends and sides, forms two principal compartments, or centres, of two different complexions, light and dark, alternating diagonally, and divided by a broken diagonal frame.

I claim—

First, the configuration, or linear arrangement, substantially;

Second, the configuration, in combination with the arrangement and location of the shades and colors; and

Third, especially the dark compartment, or centre, formed by the junction of the two halves at A and B. (See design.)

The drawings represent more fully, clearly, and exactly, than any written description can do, the nature and extent of my invention.

What I claim as my invention, and desire to secure by Letters Patent, is—

The design or pattern for floor oil-cloths herein set forth.

JOHN T. WEBSTER.

Witnesses:

J. B. NONES,
THOMAS JEFFERY.
